UNITED STATES PATENT OFFICE.

PAUL TARAS, OF LEONIA, NEW JERSEY.

CONTAINER.

Application filed October 15, 1923. Serial No. 368,586.

To all whom it may concern:

Be it known that I, PAUL TARAS, a citizen of the United States, residing at Leonia, Bergen County, New Jersey, have invented 5 certain new and useful Improvements in Containers, of which the following is a description.

My invention relates to containers, and particularly to containers made of tin, such 10 as are commonly employed for holding lubricating oil for internal combustion engines. The object of my invention is to provide a container from which the oil may be conveniently poured, which may be easily 15 sealed or closed, which will be practically non-refillable, and which will be relatively simple and cheap to manufacture.

In the accompanying drawing, I have shown the preferred embodiment of my invention, and the invention, together with its 20 advantages will be readily understood from a description of this drawing.

Referring to the drawing, Fig. 1 is a perspective view of the container, with the 25 cap in open position; Fig. 2 is a sectional view of the combined cap and spout showing the same in position to close the opening in the container; and Fig. 3 is a sectional view of a modified cap with its associate spout 30 shown in open position.

Referring in detail to the drawing, the container 1 is preferably made of tin and may be of any desired shape and size. It is provided on its top and preferably near one 35 edge with an opening 2. The opening 2 is surrounded by the screw-thread projection 3 adapted to receive the cap or cover 4. The cap 4 is provided with a spout 5 projecting horizontally from the side of the cap. The 40 cap is threaded at 6 to engage the threads 3 and is provided in its upper portion with compressible material such as cork 7. When the cap is screwed down as shown in Fig. 2, the cork 7 rests on and presses against the shoulder 8 and thereby effectively seals the 45 container. When the cap and its associated spout are turned so as to unscrew the engagement with the container, the cork 7 is lifted and the spout 5 is put in communica-

tion with the liquid in the container. Since 50 the spout projects over the side or edge of the container the liquid may be conveniently poured therefrom. When the cap is screwed down so as to bring the seal 7 into engagement with shoulder 8 the spout is disposed 55 over the top of the container, as shown in dotted lines in Fig. 1. In this position, it can be readily stored or shipped. The cap 6 is also provided with an air inlet 11.

In Fig. 2, I have shown, in dotted lines at 60 9, an additional seal. This is of the type which is usually affixed when the container is originally filled, and by screwing the cap entirely off this seal, can readily be pushed or moved out of position. Its object is to 65 prevent the container from being refilled before it reaches the consumer.

In Fig. 3, I have shown a modification in which the seal 9 may be dispensed with. The construction shown in this figure is the 70 same as that shown in the other figures, except that the cap or cover is arranged so that it cannot be entirely removed. This is effected by providing a shoulder 10' adapted to contact with the shoulder 10, 75 thereby limiting the distance which the cap can be unscrewed. Due to the shape of the spout, it is difficult and practically impossible to refill the container without removing the cap. 80

Having now described my invention, what is claimed is:

1. A liquid container having an opening therein, a screw cap for the opening, an air inlet on the side of said cap, a resilient element fixed to the inside of the top wall of said cap, a spout handle opposite said air inlet formed integral with the cap extending from the side thereof and below said element the cap being so mounted that when it 90 is turned a limited amount in one direction the container is open through the spout, and when it is turned in the other direction it operates to seal the container with said element. 95

2. A liquid container having an opening therein, a threaded collar surrounding said opening having an external flange at its

outer end, a screw cap for said opening having a shoulder whereby the outward movement of the cap is limited by said flange an air inlet in the side thereof, a resilient element fixed to the inside of the top wall of said cap, a spout handle formed integral with said cap extending from the side thereof below said element opposite said air

inlet, the cap being so mounted that when it is turned a limited amount in one direction the container is open through the spout, and when it is turned in the other direction it operates to seal the container with said element. 10

PAUL TARAS.
